UNITED STATES PATENT OFFICE

2,598,080

FLOOR SANDING MACHINE

Joseph E. Swalinkavich, Jr., Robbinsdale, Minn.

Application April 2, 1949, Serial No. 85,157

15 Claims. (Cl. 51—174)

1

My present invention relates to improvements in floor sanding machines.

An object of this invention is to provide an endless abrading belt that runs under a work-supported drum and over an upper driven roll of different diameters, whereby the work-engaging area of the belt passing under the drum is constantly changing its circumferential relation to the periphery of the drum during each cycle of the belt.

Further objects and advantages of this invention are that the abrading belt has a continuous and unbroken abrading surface and in which the belt is given steady and uninterrupted pull, without chatter; that produces an even and smooth sanded surface throughout the full width of the belt.

A further object of this invention is to provide such an abrading belt that has an extremely large abrading area resulting in long life; that wears evenly throughout its entire width and length, whereby the entire abrading surface has the same sharpness as the same wears down; that has a relatively long cooling period from the time it leaves the drum until its return; that tends to materially reduce the gumming of the belt and the loading of the interstices in the abrading material with resulting friction; and that flexing of the long upwardly moving run of the abrading belt loosens and discharges dust and other matter in said interstices.

A still further object of the invention is to provide a floor sanding machine having a section that is removable from the main body of the machine without disturbing any of the parts thereof or their adjustments.

Other objects of the invention will be apparent from the following description, reference being had to the drawings.

To the above end, generally stated, the invention consists of the novel devices and combination of devices hereinafter described and defined in the claims.

In the accompanying drawings, which illustrate the invention, like characters indicate like parts throughout the several views.

Referring to the drawings:

Fig. 1 is a right-hand side elevational view of the improved sanding machine;

Fig. 2 is a left-hand side elevational view of the same;

Fig. 3 is a view corresponding to Fig. 2, with the exception that some parts are broken away and other parts are shown in central vertical section;

2

Fig. 4 is a view partly in elevation and partly in section taken on the line 4—4 of Fig. 3;

Fig. 5 is a fragmentary detail view partly in plan and partly in section taken on the irregular line 5—5 of Fig. 2;

Fig. 6 is a plan view of the improved sanding machine;

Fig. 7 is a fragmentary detail view partly in elevation and partly in section taken on the line 7—7 of Fig. 1, on an enlarged scale;

Fig. 8 is a fragmentary detail view partly in elevation and partly in section taken on the irregular line 8—8 of Fig. 7;

Fig. 9 is a view corresponding to Fig. 2, with the exception that certain parts are broken away and other parts are sectioned on the line 9—9 of Fig. 6;

Fig. 10 is a fragmentary view in rear elevation of the frame and the combined motor bed and driven roll assembly mount;

Fig. 11 is a fragmentary detail view partly in elevation and partly in section taken on the line 11—11 of Fig. 9;

Fig. 12 is a fragmentary detail view partly in plan and partly in section taken on the line 12—12 of Fig. 7; and

Fig. 13 is a rear end view of the suction fan housing and attached motor, some parts being broken away and other parts sectioned.

30 The improved sanding machine includes a housing 13 for an abrading belt and associated parts, as will presently appear. This housing 13 is rearwardly inclined and the top 14 thereof is semicircular from front to rear. The front member 15 and the rear member 16 of the housing 13 are tangential to the top 14 and in slightly downwardly diverging relation. The bottom of the housing 13 is open and in its side member 17 is a wide aperture 18 at the transverse center thereof. This aperture 18 extends through the open bottom of the housing 13 and nearly to the top thereof. The other side member 19 of the housing 13 has in its upper half an aperture 20 similar to the corresponding part of the aperture 18. Both upper ends of the apertures 18 and 20 are semicircular and concentric to the housing top 14.

As an integral part of the housing 13, at the back thereof, is a dust scoop chamber 21 having a back member 22, a bottom member 23, that is downwardly and forwardly inclined to the bottom of the housing 13, and side members 24. This chamber 21, at its top and front, is open to the interior of the housing 13 at the back there-

of. In the back member 22 is a large annular dust escape hole 25.

The improved sanding machine further includes a frame 26 having two side members 27 and 28, the former being secured to the rear member 16 of the housing 13 by screws 29. This side member 27 is in the plane of the housing side member 17 and projects rearwardly therefrom. That portion of the side member 28, rearwardly of the housing 13, is identical with the side member 27 and the front portion thereof extends to the front of said housing. The side member 28 is spaced outwardly of the housing 13 to leave a narrow compartment 30 therebetween. Integral with the front end of the side member 28 is a front member 31 that contacts said housing and has the same contour as its front member 15, except its upper end portion which curves inwardly. Spacing lugs 32, integral with side member 28, engage the housing side members 19 and 20 are secured thereto by screws 33.

Wheel housings 34 are formed in the rear end portions of the side members 27 and 28 by in-setting the same. A pair of axial floor wheels 35 in the wheel housings 34 are journaled to the sides thereof. The side members 27 and 28, at their rear end portions, are connected and held laterally spaced by a hinge rod 36. This hinge rod 36 has shoulders 37 that impinge the inner sides of the side members 27 and 28 and washers and cap nuts 38 are applied to the outer end portions of said hinge rod.

A flat motor bed 39 extends upwardly and forwardly between the frame side members 27 and 28. Integral with the rear end of the motor bed 39 and the right-hand side thereof are depending flanges 40 and 41, respectively, the former having, at its end portions, a pair of depending ears 42. These ears 42 are detachably secured by screws 43 to hubs 44 on the hinge rod 36 and support the motor bed 39 for limited vertical swinging movement. Collars 45 on the hinge rod 36 hold the hubs 44 with a working fit between the side members 27 and 28 and said collars. The motor bed 39, at its front end, is spaced from the housing 13 to leave a passageway 46 therebetween. An electric motor 47 is mounted on the motor bed 39, with its armature shaft 48 extending transversely thereof. The motor 47 is secured to its bed 39 by nut-equipped studs 49 anchored to said bed and extending through slots 50 in the base 51 of the motor 47.

The motor bed 39 has a long narrow forwardly projecting extension that affords a mount 52 for driven roll assembly that is integral with the left-hand side portion of the bed and overlies the compartment 30. Integral with the left-hand side of the motor bed 39 and the mount 52 is a depending flange 53 and integral with the front end of the bed 39 and the flange 53 is a front member 54 closely positioned to the upper end of the front member 31. The flanges 41 and 53 extend between the frame side members 27 and 28 and have a close working fit therewith. The mount 52, the flange 53 and the front member 54 afford a top closure for the compartment 30. A transverse channel 55 is formed in the mount 52 and its flange 53 at the front member 54.

The mount 52 carries a driven roll assembly 56 that extends through the aperture 20 and transversely through the housing 13. This assembly 56 includes a cradle 57, the left-hand end portion of which extends through the channel 55 in the mount 52 and has on its sides trunnions 58 mounted in the sides of said channel and sup-

porting said cradle for hinge-like movement in the plane of the housing 13. The end of the cradle 57, outwardly of the channel 55, affords an integral bearing 59 in the form of a flat plate. The outer end of the cradle 57 affords a bearing 62 in the aperture 18. This bearing 62 is also in the form of a flat plate detachably secured by screws 63 to the body of the cradle 57.

On the under side of the cradle 57 is a pair of axially aligned rollers 64 and 65 that rest on cams 66 and 67, respectively. The roller 64 is turnably mounted on a pin 68 secured, at its end portions, in the flange 53 and a depending ear 69 on the under side of the cradle 57 at its transverse center. The roller 65 is turnably mounted on a pin 70 secured at its end portions to the prongs of a yoke-like bearing bracket 71 provided with an upstanding screw stud 72 having threaded engagement with a boss 73 on the under side of the cradle 57 at its outer end. A lock nut 74 on the screw stud 72 impinges the cradle 57. The cradle 57 further includes a reinforcing rib 75 on its under side and transverse center. A driven roll 76 in the housing 13 has on one of its end portions integral twin V pulleys 77 that are between the housing side member 17 and the bearing 59. Trunnions 78 on the roll 76 and the outer pulley 77 are mounted in the bearings 62 and 59, respectively. A pair of matched V belts 79 run over the V pulleys 77 and V pulleys 80 on the armature shaft 48 of the motor 47.

A guard 81 is provided for the belts 79 and includes a side member 82 and a cover member 83 that is integral with the ends and top of said side member. The side member 82 is in the plane of the frame side member 28 and its lower portion overlaps the motor bed 39 and the mount 52. The belt guard 81, at its front, is detachably secured to the mount 52 by screws 84 and to the rear end portion of the motor bed 39 by screws 85. The cover member 83 of the belt guard 81, at its inner edge portion, engages the respective side of the housing 13. The side member 82 of the belt guard 81 has an opening 86 in which the bearing 59 fits. The tops of the bearings 59 and 62 are semicircular to correspond to the upper ends of the opening 86 and the aperture 20, respectively, with which they are substantially concentric.

Within the housing 13, below the roll assembly 56, is a drum assembly 87 that includes a casting that includes a body 88 in the form of a long horizontal bar that extends transversely through the housing 13. On the left-hand end of the body 88 is an integral upstanding flat plate 89 secured by screws 90 to the housing side member 19 with its upper end flush with the bottom of the aperture 20 therein. A pair of axially aligned bearings 91 and 92 are formed, the former with the plate 89 and the latter on the other end portion of the body 88. On the upper side of the body 88, at its transverse center, is a reinforcing rib 93, the ends of which are integral with the plate 89 and bearings 91 and 92.

A tubular rock shaft 94 of a relatively large diameter, is mounted in the bearings 91 and 92. Extending through the tubular shaft 94 is a shaft 96 journaled in bushings 97 secured in the end portions of the tubular shaft 94. The shaft 96 extends obliquely substantially in a horizontal plane, through the tubular shaft 94 and the end portions thereof are journaled in the bushings 97 eccentric to the axis thereof and on opposite sides of said axis, see Fig. 12. The shaft 96 extends outwardly of the bushings 97 and the cams

66 and 67 are rigidly secured thereto. Obviously, by turning the shaft 96 in the bushings 97, one of the cams 66 and 67 will be raised and the other lowered and thereby move the cradle 59 and tilt the roll 76 on its longitudinal axis in a vertical plane. Each cam 66 and 67 is a vertically disposed flat plate, the top of which is substantially semicircular. The axes of the cams 66-67 are rearwardly offset from the axis of the shaft 96 to which they are secured. The rollers 64 and 65 rest on the cams 66-67 substantially over their axes. A depending bearing plate 98 is detachably secured to the right-hand end of the body 88 by screws 99. A drum 100, of a diameter considerably larger than that of the roll 76, has on its ends trunnions 101 journaled in the housing side member 17 and the bearing plate 98. The roll 76 and the drum 100 each has a resilient sleeve on its periphery of rubber, felt or other suitable cushioning material. A wide endless belt 103, having on its outer face an abrading material, runs over the roll 76 and the drum 100.

The cams 66-67 are raised to lift the roll 76 and tighten the belt 103 or lowered to loosen said belt and permit the same to be removed edgewise from the roll 76 and the drum 100 through the aperture 18 in the housing 13, by the following manually operated connections, to wit: a long screw rod 104 having on its outer end a knob 105, by which it may be turned, extends into the compartment 30 through a hole 106 in the front member 31. The screw rod 104 also extends through a bearing 107 therefor and has threaded engagement with a nut-acting member 108 that extends between and is swivelled to a pair of depending plates 109 secured to the cam 66 on opposite sides thereof. The bearing 107 is mounted in the housing side member 17 and the frame side member 28 to turn about a horizontal axis. A coiled spring 110 encircling the screw rod 104 is held compressed between the bearing 107 and a collar 111 on said screw rod and yieldingly holds the cams 66 and 67 where adjusted. The position of the cams 66-67 in the drawings supports the roll assembly 56 in a lowered position to put slack in the abrading belt 103. To tighten the abrading belt 103, the roll assembly 56 is lifted by manipulating the screw rod 104 to swing the cam 67 upwardly and forwardly. This movement of the cam 67 imparts a like movement to the cam 66 by means of the shaft 96 to which both cams 66-67 are rigidly connected.

It may be here stated that by removing the abrading belt 103 from the roll 76 and the drum 100 and the screws 43 from the hubs 44, the motor bed 39 may be lifted with the motor 47 thereon to clear the frame side member 28 and then moved outwardly to withdraw the entire roll assembly 56 from the housing 13 through the aperture 20 and openings 86, without disturbing the belts 79 or any other of the assembly parts.

The improved sanding machine is moved and guided by a handle 112 in the form of a tube secured at its inner end in a hollow T-casting 113 turnably mounted on a hinge rod 114 that extends through aligned holes in the head of said casting and a pair of upstanding bearings 115 between which the casting 113 extends. The bearings 115 have outturned flanges 116 which, together with said bearings, rest on the top of the housing 13 and are secured thereto by screws 117. On the outer end portions of the hinge rod 114 are washers 118 and cap nuts 119. A cast head 120 is secured to the outer end of the handle 112. On the right-hand side of the head 120 is a hand

hold 121, on the under side thereof is a depending hand grip 122 and on the right-hand side of said head is a turnable hand grip 123 axially aligned with the hand hold 121. The hand grip 123 is secured at its inner end to a long pin 124 turnably mounted in the head 120 and the hand hold 121.

In case the abrading belt 103 drifts on the roll 76 and drum 100, said roll may be tilted axially in a vertical plane to return said belt to its normal position by the following manually operated connections: a depending lever 125 is secured to the hand grip 123 at its inner end to be operated thereby. This lever 125 is provided on its outer side with an integral thumb-piece 126. A second lever 127 is pivoted on the left-hand end portion of the hinge rod 114 between a washer 128 that impinges the adjacent bearing 115 and the respective washer 118. This second lever 127 has on its inner side a wide reinforcing rib 129 that extends centrally and longitudinally thereof and provided at its longitudinal center and in the plane thereof with a boss 130. A long connecting link 131 is pivoted at one end to the outer end of the lever 125 and pivoted at its other end to the boss 130. A depending lever 132 for turning the tubular shaft 94 has on one end a collar 133 fitted on the ends of said shaft in the housing 13 and secured thereto in different relative circumferential adjustments by set screws 134. Swiveled on the outer end portion of the lever 132 is a guide 135. A long rod 136 is pivotally attached at one end to the outer end of the lever 132 and its other end portion extends through a hole in the guide 135 and secured thereto, when endwise adjusted therein to vary its operative length, by a set screw 137.

Formed in the top member 14 and the side member 17 of the housing 13 is a sight opening 138 through which the operator of the sanding machine may watch the abrading belt 103 to see that it does not drift on the drum 100. In case the abrading belt 103 drifts on the drum 100, it is only necessary for the operator to manipulate the lever 125 to tilt the roll 76 in the proper direction to return the abrading belt 103 to its correct position on the drum 100.

Dust cut from a floor being sanded by the machine is thrown by the abrading belt 103 into the dust scoop chamber 21 where it is drawn through the passageway 25 into the fan housing 139 by a suction fan 140 in said housing. This suction fan 140 is operated directly by an electric motor 141 secured to the housing 139. From the housing 139, the dust is delivered by the suction fan 140 into a long flexible metal conduit 142. The conduit 142 is connected just above the fan housing 139 to the back member 16 of the housing 13 by a two-part clamp 143. From the clamp 143, the conduit 142 extends upwardly to a point just above the motor 47 and then horizontally rearward and into a dust-collecting bag 144. This dust bag 144 has a neck portion 145 through which the conduit 142 extends and is secured thereto by a tied piece of tape 146. The dust bag 144 also has a looped piece of tape 147 placed over the hand hold 121 and supports said dust bag therefrom. Formed in the upper rear portion of the dust bag 144 is a dust discharge opening 148 through which said bag is emptied. This opening 148 is normally closed by any one of the well known separable fasteners 149 including slide operated interlocking members. A baffle 16', in the form of a horizontal bar, is secured to the rear member 16 with the housing 13. This

baffle 16' substantially fills the space between the housing rear member 16 and the upper run of the abrading belt 103 to prevent dust in the scoop chamber 24 from following said belt.

An electric bulb 150, for illuminating the work in advance of the sanding machine, is mounted in a socket 151 secured to the front member 15 of the housing 13. Also secured to the front member 15 is a hood 152 for the electric light bulb 150. In the front member 15 is a glass window 153 directly back of the electric light bulb 150 through which the interior of the housing 13 is illuminated. The electric light wiring for the electric motors 47 and 141 and the electric light bulb is indicated as an entirety by the numeral 154 with the exception of the switch 155 in the head 120 of the handle 112 and the coupling member 156 applicable to an extension cord, not shown, leading from any suitable outlet. The handle 112, the casting 113 and the head 120 afford a conduit for certain parts of the wiring 154.

From a broad viewpoint, the housing 13 may be considered to be a main frame and the frame 26 a secondary frame.

From what has been said, it will be understood that the floor sanding machine described is capable of modifications as to details of construction and arrangement within the scope of the invention herein described and claimed.

What I claim is:

1. In a floor sanding machine, a frame, a lower drum journaled in the frame, a cam assembly in the frame including a pair of eccentric cams connected for common movement in vertical planes, means for operating the cams, an upper driven roll assembly in the frame including a cradle supported on the cams, a driven roll journaled in the cradle, an endless abrading belt arranged to run under the drum and over the driven roll, said drum supporting the frame from the floor and pressing the abrading belt thereon, a motor, and driving connections from the motor to the driven roll.

2. In a floor sanding machine, a frame, a lower drum journaled in the frame, a cam assembly in the frame including bearings, a tubular rock shaft journaled in the bearings, an inner shaft journaled in the rock shaft and extending outwardly thereof, the end portions of the inner shaft being eccentric to the axis of the rock shaft and on opposite sides thereof substantially in a horizontal plane, an eccentric cam on each end of the inner shaft, means for turning the rock shaft to simultaneously raise or lower the cams, other means for turning the inner shaft relative to the rock shaft to raise one cam and lower the other, an upper driven roll assembly including a cradle supported on the cams, a driven roll journaled on the cradle, an endless abrading belt arranged to run under the drum and over the driven roll, said drum supporting the frame from the floor and pressing the abrading belt thereon, a motor, and driving connections from the motor to the driven roll.

3. The structure defined in claim 2 in which the means for turning the inner shaft relative to the rock shaft comprises a long screw rod, a swiveled bearing in which the screw rod is mounted for compound turning and endwise sliding movement, a swiveled nut-acting member attached to one of the cams with which the screw rod has threaded engagement, a collar on the screw rod between the bearing and nut-acting member, and a coiled spring encircling the screw rod and com-

pressed between the bearing and nut-acting member.

4. The structure defined in claim 2, further including a handle for moving and guiding the sanding machine having a turnable hand grip, and in which structure the means for turning the rock shaft includes a lever actuated by the hand grip.

5. The structure defined in claim 2, further including rollers on the cradle and resting on the cams.

6. The structure defined in claim 2 in which the bearings for the drum are connected and secured to one side of the frame and in which the cradle is supported on the same side of the frame as the bearings, said frame having in its other side an aperture through which the abrading belt may be removed edgewise from the drum and the upper roll and from the frame.

7. In a floor sanding machine, a main frame, a secondary frame secured to the main frame and having floor wheels, a lower drum journaled in the main frame and supporting the same from the floor, a motor bed removably hinged to the secondary frame for movement in a vertical plane and having an extension mount at one side of the main frame, an upper driven roll assembly including a cradle, extending transversely through the main frame and attached at one end to the mount extension, means supporting the mount extension and the cradle at its outer end portion and operable to simultaneously raise or lower said mount extension and the cradle, a driven roll journaled on the cradle, an endless abrading belt arranged to run under the drum and over the driven roll, said drum supporting the main frame on the floor and pressing the abrading belt thereon, a motor on the motor bed, and driving connections from the motor to the driven roll.

8. The structure defined in claim 7 in which the cradle is hinged to the mount extension for vertical movement.

9. In a floor sanding machine, a main frame, a secondary frame secured to the main frame and having floor wheels, a lower drum journaled in the main frame and supporting the same from the floor, a motor bed removably hinged to the secondary frame for movement in a vertical plane and having a mount extension at one side of the main frame, an upper driven roll assembly including a cradle extending transversely through the main frame and hinged at one end for movement in a vertical plane, a pair of cams, a roller on the mount extension resting on one cam, a second roller on the outer end portion of the cradle and resting on the other cam, means for operating the cams to simultaneously raise the mount extension and lower the cradle on opposite sides of the main frame and vice versa, other means for operating the cams to impart reverse raising and lowering movements to said mount extension and cradle, an endless abrading belt arranged to run under the drum and over the driven roll, said drum supporting the main frame from the floor and pressing the abrading belt thereon, a motor on the motor bed, and driving connections from the motor to the driven roll.

10. In a floor sanding machine, a main frame having side members, an idle drum and a pair of floor wheels journaled on the frame and supporting the same with lower edges of the side members closely positioned above their floor-engaging surfaces, a horizontally disposed sec-

ondary frame in the main frame and hinged thereto at its rear end for raising and lowering movements, movable means on the main frame supporting the secondary frame at its front end, a cradle fixed to the front end portion of the secondary frame, a driven roll journaled in the cradle, an endless abrasive belt arranged to run under the drum and over the driven roll, means for driving the roll, means for operating the movable means to raise the secondary frame and tighten the abrasive belt, and vice versa.

11. In a floor sanding machine, a main frame, an idle drum journaled on the main frame, a horizontally disposed secondary frame hinged at its rear end to the main frame to move about a horizontal axis and with its front end portion above the drum, a roll journaled on the front end portion of the secondary frame, adjustable members on the main frame supporting the secondary frame, an endless abrading belt arranged to run under the drum and over the roll, means for adjusting the adjustable members to raise the secondary frame to tighten the belt, and vice versa, a motor on the secondary frame, and driving connections from the motor to the roll.

12. In a floor sanding machine, a main frame, an idle drum journaled on the main frame, a horizontally disposed secondary frame hinged at its rear end to the main frame to move about a horizontal axis and with its front end portion above the drum, a roll journaled on the front end portion of the secondary frame, a pair of adjustable members on the main frame supporting the secondary frame, an endless abrading belt arranged to run under the drum and over the roll, means for imparting one adjustment to the adjustable members to raise the secondary frame to tighten the belt, and vice versa, a second means for imparting a second adjustment to the adjustable members for tilting the roll relative to the axis of the drum, a motor on the secondary frame, and driving connections from the motor to the roll.

13. In a floor sanding machine, a main frame, an idle drum journaled on the main frame, a horizontally disposed secondary frame hinged at its rear end to move about a horizontal axis and with its front end portion above the drum, a cradle extending transversely of the secondary frame and hinged thereto at one end to turn about a horizontal axis, a pair of adjustable mem-

bers on the main frame, a pair of rollers journaled on the cradle and resting on the adjustable members and supporting the secondary frame therefrom, the roller on the opposite end of the cradle from its hinged end being adjustable to tilt the cradle, a roll journaled in the cradle, an endless abrading belt arranged to run under the drum and over the roll, means for simultaneously imparting one adjustment to the adjustable means to raise the cradle and tighten the belt, and vice versa, a second means for simultaneously imparting a second adjustment to the adjustable means to tilt the cradle relative to the axis of the drum, a motor on the secondary frame, and driving connections from the motor to the end of the roll at the hinged end of the cradle.

14. In a floor sanding machine, a frame, an idle drum journaled on the frame, a cradle, means mounting the cradle on the frame for raising and lowering movements over the drum, a pair of adjustable members on the frame supporting the cradle, an endless abrading belt arranged to run under the drum and over the roll, means for simultaneously imparting one adjustment to the adjustable means to raise the cradle and tighten the belt, and vice versa, a second means for simultaneously imparting a second adjustment to the adjustable means to tilt the cradle relative to the axis of the drum, a motor on the cradle mounting means, and driving connections from the motor to the roll.

15. The structure defined in claim 14, further including a resilient sleeve on the drum held compressed by the tightening of the belt.
